UNITED STATES PATENT OFFICE.

DAVID EDGAR RICE, OF BROOKLYN, NEW YORK.

STENCIL-STAMP.

1,230,783.

Specification of Letters Patent. Patented June 19, 1917.

Application filed September 8, 1915. Serial No. 49,431.

To all whom it may concern:

Be it known that I, DAVID EDGAR RICE, residing at Brooklyn, in the county of Kings and State of New York, have invented certain new and useful Improvements in Stencil-Stamps, of which the following is a specification.

This invention relates to a stencil stamp.

The object of the invention is to provide means whereby the subject matter or characters to be impressed by the stamp may be altered indefinitely at will.

A more detailed object is to provide a hand stamp comprising an ink pad and a stencil member carried thereby, the stencil member being detachable and interchangeable with other like stencil members, the idea being that stencil members having different characters or subject matter formed therein may be applied for coöperative use with the pad at will.

A further object is to provide a simple, efficient and practical means whereby the stencil members are rendered readily attachable and detachable.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings which are to be taken as a part of this specification, and in which I have shown a merely preferred form of embodiment of the invention:

Figure 1 is a perspective view of a stencil stamp constructed in accordance with this invention, the device being shown inverted.

Fig. 2 is a transverse, vertical central sectional view through the device shown in Fig. 1, the same being shown in upright or operating position.

Fig. 3 is an enlarged detail sectional view of the stencil member detached.

Fig. 4 is a perspective view illustrating a modified means of retaining the stencil member in position.

Fig. 5 is a plan view illustrating a fur-

ther modification of the means for retaining the stencil member in position.

Fig. 6 is a perspective view illustrating a further modification.

Fig. 7 illustrates a modified form of ink pad; and

Fig. 8 is a detailed sectional view illustrating the manner of retaining the ink pad of Fig. 7 in position.

Referring to the drawings for a detailed description of the structure illustrated, the reference character L indicates the body portion of the stamp and G the ink pad carried thereby.

The body portion L is provided with a suitable handle 1, by means of which the stamp may be readily manipulated. The pad G is held in place preferably by having its opposite longitudinal edges turned laterally upon the opposite sides of the body and being received in suitable depressions, as 2, formed to receive them. A pair of plates 3, preferably of metal, is fixed to opposite sides of the body so as to overlie the turned portions of the pad and retain the same against displacement.

The stencil member may be formed in any manner, but preferably comprises a rectangular frame 4, over which a sheet of stencil paper H is stretched. The inside dimensions of the frame 4 are such as to coincide substantially with the outside dimensions of the pad G. The edges as 5, of the plates 3, are turned slightly outwardly so as to grip firmly against the inner edges of the frame along at least two sides, substantially as indicated particularly in Fig. 2 of the drawings. This engagement is sufficient to retain the frame against displacement with the stencil paper in close contact with the surface of the ink pad. At the same time the frame may be readily detached at will.

The structure shown in Fig. 4 is substantially the same as that shown in the preceding figures, except that in this instance the plates 3 are provided with lateral extensions 6, having turned edges 7 for engaging the outer edge of the frame 4. Portions of the extensions 6 are cut away, as at 8, for facilitating handling of the frame.

The structure shown in Fig. 5 is the same as that shown in Fig. 4, except that in Fig.

5 one of the extensions 6 is separately formed and pivotally mounted at one end, as at 9, so as to be easily swung into and out of position for gripping the edge of the frame. Obviously both of the extensions 6 may be thus connected, if desired, but it is believed that 10 one is sufficient. In this figure the separately formed piece is indicated by the reference character 10, and is shown by full lines, 15 partly in section, in position to hold the frame, and by dotted lines as 10^a, in position free of the frame.

In the modification Fig. 6, the frame is entirely omitted and the edge portions, as 11, 15 of the stencil paper 12 are turned downwardly upon the side surfaces of the stamp and held in such position by a separately formed band 13, which is readily movable into and out of clamping position, it being 20 slidably supported upon the side walls of the stamp.

The ink pad in all instances may be made of a single sheet of felt, flannel, or other suitable material, but it is preferably provided with reinforcing strips 15 as shown in Figs. 7 and 8. These strips are fixed to the longitudinal edges of the material of the pad, preferably by being punched into the material from opposite sides, as at 16, the 25 strips being U-shaped in cross section, and the edge of the material of the pad being received between the legs of the strip. By this means the pad may be readily handled and inserted or removed from connection 30 with the body portion of the stamp when desired.

The portions of the plates 3, which overlie the depressions 2 and bear against the turned portions of the pad, are resilient so 40 as to press yieldingly upon the pad.

Where the strips 15 are employed the same are received within the depressions 2 and receive the pressure from the plates 3. In order to render the grip of the plates 45 more effective, the walls of the depressions 2 may be inclined, as shown in Fig. 2, if desired, or the portions of the plates overlying the depressions may be inclined, as shown in Fig. 8, or both the overlying 50 portions of the plates and the wall of the depression may be inclined if desired. In cases where the strips 15 are employed, said strips are preferably shaped so as to be of greater width at their inner edges than at 55 their outer edges, as indicated in Fig. 8. Also the punched portions 16 in the strips may serve as relative shoulder portions to improve the grip of the plates 3.

It will, of course, be understood that the 60 stencil paper H is adapted to be perforated or otherwise operated upon in any manner well known in the art for permitting passage of ink from the ink pad through portions of the paper when the stamp is pressed

against a surface upon which it is desired 65 to apply an impression from the stencil. The stencil paper may be operated upon in an ordinary typewriting machine for this purpose, prior to being attached in position upon the ink pad. 70

In use the plates 3 coöperate with the side walls of the depressions 2, so as to constitute recesses or pockets, each having a resilient wall portion by means of which the edges of the ink pad are resiliently retained. 75

In Fig. 5 the reference numerals 14 indicate small apertures through which a pointed instrument may be inserted to force the stencil member outward, if desired.

As shown in the drawings, the face of 80 the body portion of the stamp may be formed on a curve so that in operation the impression may be made upon the surface to be printed upon with a rocking motion of the stamp. This operates to effectively 85 force ink from the pad through the stencil and insures an even distribution of ink through the printing characters.

As many changes could be made in this construction without departing from the 90 scope of the following claims, it is intended that all matter contained in the above description or shown in the accompanying drawing shall be interpreted as illustrative only and not in a limiting sense. 95

Having thus described my invention what I claim as new and desire to secure by Letters Patent is:

1. A device of the class described, comprising a body member having recesses 100 formed in opposite sides thereof, an ink pad overlying one face of the body member and having edge portions received in said recesses, reinforcing members attached to said edge portions also received in said recesses, plates carried by the body member having resilient portions overlying the recesses in engagement with said reinforcing members, and a stencil member overlying 105 the ink pad. 110

2. A device of the class described, comprising a body member having recesses formed in opposite sides thereof, an ink pad overlying one face of the body member and having edge portions received in said 115 recesses, reinforcing members attached to said edge portions also received in said recesses, plates carried by the body member having resilient portions overlying the recesses in engagement with said reinforcing members, a stencil member, and said plates also engaging said stencil member to retain the same in position overlying the ink pad. 120

3. A device of the class described, comprising a body member, an ink pad carried thereby, reinforcing members carried by edge portions of the ink pad, the reinforcing members being provided with raised por- 125

tions, resilient retaining means carried by the body member engaging said raised portions to resiliently retain the ink pad in position, and a stencil member overlying 5 the ink pad.

4. A device of the class described, comprising a body member having recesses at opposite sides thereof, an ink pad overlying one surface of the body member and having edge portions extending into said recesses, said recesses being widest at their bottoms so as to retain the edge portions of the ink pad against detachment, and a stencil member overlying the ink pad between 10 said recesses.

5. A device of the class described, comprising a body member, an ink pad carried thereby, a stencil member overlying the ink pad, said stencil member comprising a frame having a sheet of stenciled material stretched thereover, and means carried by the body member engaging said frame to retain the stencil member in position.

6. A device of the class described, comprising a body member, an ink pad carried thereby, a stencil member overlying the ink pad, said stencil member comprising a frame having a sheet of stenciled material stretched thereover, and means carried by 20 the body member engaging the inner edge portion of the frame to retain the stencil member in position.

7. As an article of manufacture, a stencil stamp, comprising a body member, an ink pad carried thereby, a stencil member having a thickened marginal portion providing oppositely disposed shoulders, and means carried by the body member for engaging against said shoulders to detachably retain 30 the stencil member in position overlying the ink pad.

8. As an article of manufacture, a stencil stamp, comprising a body member, an ink pad carried thereby, a stencil member having a thickened marginal portion providing oppositely disposed shoulders, and a pair of 40 spring plates carried by the body member resiliently engaging said shoulders to retain the stencil member in position overlying the ink pad.

9. A device of the class described, comprising a body member, an ink pad carried upon one surface thereof and having edge portions extending over adjacent surfaces of 50 said body member, a pair of spring plates carried by the body having their inner surfaces pressing against said edge portions to clamp said edge portions against the body and thereby retain the ink pad upon the body and thereby retain the ink pad upon the body, and a stencil member overlying the ink pad and being retained by said spring plates.

10. A device of the class described, com-

prising a body member, an ink pad carried 65 upon one surface thereof and having edge portions extending over adjacent surfaces of the body, a pair of spring plates carried by the body having their inner surfaces pressing against said edge portions to clamp 70 said edge portions against the body and thereby retain the ink pad upon the body, and a stencil member overlying the ink pad and being retained by said spring plates by having opposingly disposed shoulders 75 formed thereon disposed to be frictionally resiliently engaged by outer surface portions of said spring plates.

11. A hand stamp, comprising a rectangular block of material, a handle projecting 80 from the top surface thereof, an ink pad arranged upon the bottom surface thereof, said ink pad comprising a sheet of suitable material, reinforcing means fixed to the edge portions of said material disposed to 85 lap opposite side surfaces of said block, means carried at said opposite sides of the block for engaging the reinforcing means to retain the ink pad stretched over the bottom surface of the block, and a stencil member 90 operatively engaging the ink pad.

12. A device of the class described, comprising a body member, an ink pad carried upon one surface thereof and having edge portions extending over adjacent surfaces 95 of the body, a pair of spring plates carried by the body having their inner surfaces pressing against said edge portions to clamp said edge portions against the body and thereby retain the ink pad upon the body, reinforcing strips fixed to said mentioned edge portions disposed to be engaged by said 100 spring plates, and a stencil member overlying the ink pad and being retained by said spring plates.

13. A device of the class described, comprising a body member, an ink pad carried upon one surface thereof and having edge portions extending over adjacent surfaces of the body, a pair of spring plates carried 110 by the body having their inner surfaces pressing against said edge portions to clamp said edge portions against the body and thereby retain the ink pad upon the body, reinforcing strips fixed to said mentioned edge portions disposed to be engaged by said spring plates, said reinforcing strips comprising pieces of sheet metal bent into U cross section and receiving the edge portions between the legs thereof, and a stencil member overlying the ink pad and being retained by said spring plates.

14. A hand stamp, comprising a rectangular block of material having recesses at opposite sides thereof, each of said recesses having a resilient wall portion, a handle projecting from the top surface of said block, an ink pad arranged upon the bottom

surface of the block having edge portions disposed to lap opposite side surfaces of said block and being received in said recesses, the resilient wall portions of said recesses serving as clamp means engaging said edge portions to frictionally retain said edge portions within said recesses.

In testimony whereof I affix my signature in the presence of two witnesses.
